ADJUSTABLE COIL SPRING SUPPORT FOR UPHOLSTERED FURNITURE

Anthony Esposito, Bridgeview Apartments, Linwood Ave.,
Fort Lee, N.J. 07024
Filed June 23, 1966, Ser. No. 559,819
11 Claims. (Cl. 248—399)

This invention relates to means for supporting the bottom springs of an overstuffed piece of furniture, and more especially to apparatus that can be added to a finished chair to strengthen it, or to restore sagging springs to their original positions.

It is a common experience of owners of overstuffed furniture to have the webbing stretch or break loose so that the bottom springs of a chair or sofa sag and fail to support the seat cushions at the intended locations. Repairs are expensive and can be made properly only by someone with special skill in upholstery work.

It is an object of this invention to provide supporting means that can be added to a piece of upholstered furniture to support springs that have sagged because of some failure of the original webbing, and that can be added by anyone without dismantling and furniture. The invention can be added to a new chair or sofa so as to prevent subsequent sagging of the bottom springs or failure of the webbing.

Another object is to provide supporting means of the character indicated with connections to the furniture in position to keep all of the added structure close to the bottom of the furniture and inward from the sides of the furniture so that it is not visible to anyone in viewing the furniture from ordinary eye level.

The supporting means of this invention are kept close to the bottom of the furniture by limiting the vertical extent of the structure; and this is done by using beams to support the bottom springs instead of truss rods or other tension elements that have to extend through a substantial vertical distance in order to get angular positions for the tension on which such devices rely for their operation.

Other objects, features and advantages of the invention will appear or be pointed out as the description proceeds.

In the drawing, forming a part hereof, in which like reference characters indicate corresponding parts in all the views:

FIGURE 1 is a diagrammatic front elevation, partly broken away, showing an upholstered chair to which this invention has been applied;

FIGURE 2 is a greatly enlarged sectional view taken on the line 2—2 of FIGURE 1;

FIGURE 3 is an enlarged detail view of a part of the center hub of the supporting means shown in FIGURES 1 and 2;

FIGURE 4 is an enlarged, exploded view of a portion of the structure shown in FIGURE 2;

FIGURE 5 is a greatly enlarged sectional view taken on the line 5—5 of FIGURE 2;

FIGURE 6 is an enlarged detail view of one of the corner brackets shown in FIGURES 2 and 5;

FIGURE 7 is a bottom view of a sofa equipped with the supporting means of this invention; and

FIGURE 8 is a greatly enlarged detail view of one of the brackets shown in FIGURE 7.

FIGURE 1 shows an overstuffed chair 10 having a back 12, arms 14 and a seat 16. The chair 10 has legs 18 and it has the seat supported by springs 20 which rest, at their lower ends, on webbing 22 extending between frame elements 24 of the chair.

In service, the greatest strain and wear comes on the springs 20 which are nearest to the center of the seat 16 and it is these springs which sag as a result of stretching

2

or breaking of the web 22. The present invention provides a plate 26 which contacts with the underside of the chair bottom below the webbing and the springs 20. In the construction illustrated, the plate 26 is rectangular and substantially square, but other shapes can be used. It is advantageous to have the shape of the plate 26 approximately similar to that of the chair bottom so that it is spaced a substantially equal distance from all sides of the chair, but embodiments of the invention made for universal application to overstuffed chairs generally have the plate 26 shaped to the ideal for an average chair. The assembly has some resiliency that permits limited vertical movement of the plate 26 when a person sits in the chair.

The plate 26 is supported by two beams 32 and 34 extending across the bottom of the chair and in angular relation to one another. These beams 32 and 34 are approximately at right angles to one another but are preferably slightly greater or less than right angles, as will be explained, to accommodate the variation in the width of the chair as the seat becomes wider toward the front.

Each of the beams 32 and 34 is of composite construction. The beam 32 includes a tubular section 36 which is preferably round throughout most of its length with a flattened end portion 38. A reduced-diameter section 40 fits into the tubular section 36 with a telescopic fit, and there is preferably a set screw 42 for preventing axial movement of the reduced-diameter section 40 with respect to the tubular section 36.

A center hub 44 has a socket 46 (FIGURE 5) into which the reduced-diameter section 40 extends, and this center hub 44 forms a part of the composite beam 32. On the other side of the center hub 44, the beam 32 has another reduced-diameter section 40' which extends into a socket 46' in the center hub 44. Another tubular section 36' fits over the reduced-diameter section 40' and has a flattened end 38', similar to the end 38, previously described.

All of these structural elements of the beam 32, i.e., the sections 36, 40, 36' and 40', and the center hub 44, are stiff enough to resist any permanent deformation, and are preferably stiff enough to resist any substantial bending when subjected to the loads that they encounter when in use. The lengths of the ends of the reduced-diameter sections 40 and 40', which extend into the tubular sections 36 and 36' and into the sockets 46 and 46', are long enough to provide a rigid construction for the beam; and the wall thickness of the reduced-diameter sections 40 and 40' are preferably greater than those of the tubular sections 36 and 36' so as to compensate for the reduced diameter.

The beam 32 is connected with the frame 24 by brackets 50. Each of these brackets 50 has two legs 52 and 54, best shown in FIGURE 6, which are substantially normal to one another. Throughout most of their length, the legs 52 and 54 are reinforced by ribs 56, and there are openings 58 at the far ends of the legs 52 and 54 for connecting the bracket 50 to the frame 24 (FIGURE 2) by means of screws 60. Each of the brackets 50 is of rigid construction. By locating the screws 60 in different elements of the frame 24 on opposite sides of a line 62 where the frame elements meet at a corner, the bracket 50 serves to reinforce the corner of the frame and to prevent the frame elements from coming apart at their line of junction 62.

There is an opening 66 (FIGURE 6) in each of the brackets 54 for receiving bolts to connect the bracket with the beams and the opening 66 is preferably a slot and is preferably curved about a center which lies on a line 62' which is an extension of the line 62, when the bracket is connected with the frame of the chair at the intended location. However, in order to prevent the positioning

of the brackets 50 from being critical, and to allow for differences in the shapes and dimensions of different chairs with which the invention may be used, the opening 66 is made long enough to accommodate any differences in alignment of the beams in chairs within the range for which a particular model of the invention is intended.

The beam 34 is similar in construction to the beam 32, already described, and the beam 34 has its sections fit into sockets 72 and 72' in the same center hub 44 as contains the sockets 46 and 46'. At the center of the hub 44, there is a screw 76 which extends through the center hubs in a vertical direction and which has threads in the upper part of the hub 44. A flange 78 on the end of the screw 76 bears against the plate 26. Rotation of the screw 76 in one direction raises the plate 76 with respect to the center hub 44, and rotation in the other direction lowers the plate 26.

The center hub 44 is preferably made with the sockets 46, 46', 72 and 72' tapered in a horizontal plane so as to allow for further accommodation of the beams to chairs of somewhat different size. Referring particularly to FIGURE 3, the angle between the sockets 46 and 72 is slightly greater than 90° since these are the sockets which are intended to face forward toward the front of the chair where the frame ordinarily becomes wider. The angle between the sockets 46' and 72' is slightly less than 90° since these are the sockets which are intended to face rearwardly when the invention is installed on a chair. In the construction illustrated, the longitudinal axis of the socket 46 makes a right angle with the longitudinal axis of the socket 72' and the same is true of the longitudinal axes of the sockets 72 and 46'. To obtain greater accommodation, however, all of these sockets shown in FIGURE 3 are tapered to a larger diameter as they extend away from the middle of the center hub 44, and the width of each socket toward the small end of the taper is equal to the width of the tubular section of the beam which fits into the socket so that the beam can move angularly in the socket to give the beams an angular relation to one another which is larger or smaller than the angular relation of the sockets to one another.

Referring to FIGURE 5, however, it will be apparent that the sockets 46 and 46' do not have a taper in a vertical plane. Thus while the beam sections 40 and 40' can move angularly in the sockets 46 and 46', respectively, in a horizontal direction, they can not move angularly in a vertical plane. The same is true of the sockets 72 and 72'. This construction gives the beams stiffness in the direction in which they are loaded while providing for some freedom of movement to accommodate the structure to a wider variety of chair shapes.

The angle between the sockets 46 and 72 is preferably between about 95° and 100° and the angle between the sockets 72' and 46' is preferably between about 80° and 85°. These values are given by way of illustration. It will be evident that when the invention is made for a particular model of chair, or for a narrowly limited range of chair sizes, the tapered sockets in the center hub 44 are not required.

In order to facilitate the manufacture and assembly of the invention, the center hub 44 is preferably made in two parts, as best shown in FIGURE 4. These parts include an upper half 82 and a lower half 84. In order to obtain proper registry of these halves with one another, there are projections 86 confronting corresponding depressions on the confronting faces of the other part. Each of the parts 82 and 84 has lugs 88 with holes for receiving bolts 90 by which the parts of the center hub are held in assembled relation. The invention can be constructed so that the beam sections which fit into the center hub sockets are clamped in the sockets when the bolts 90 are tightened. This obtains the most rigid construction. The invention can also be made, however, with the tubular sections of the beams fitting into

the center hub sockets with a free sliding fit since they can not move out of the sockets after the beams are connected to the brackets 50 by bolts 94 extending through the flattened ends of the beams and through the openings in the brackets 50.

The construction shown in FIGURE 2, with the beams 32 and 34 extending diagonally across the bottom of the chair, is preferred because this connects the beams to the chair frame near the legs of the chair and does not localize stress on portions of the frame 24 mid way between the legs. Also the brackets 50 serve to brace the corners when attached as in FIGURE 2, as previously explained.

The invention can be applied to upholstered furniture by brackets located at regions remote from the furniture legs and it is advantageous to apply the invention in such a way when used on a sofa.

FIGURE 7 shows the invention applied to a sofa 100 having a frame with side elements 102 and longitudinally extending elements 104. Brackets 108 are connected to the side elements 102 at locations midway between legs 110 of the sofa, and similar brackets 108 are attached to the longitudinally extending frame members 104 at locations which are preferably equally spaced along the length of the sofa.

One of the brackets 108 is shown in detail in FIGURE 8. It has a reinforcing rib 112 and two openings 114 for receiving screws for securing the bracket to the frame of the furniture. At the other end of the bracket 108, there is a slot 116 for receiving a bolt which connects the bracket with the beams of the supporting means that extend across the bottom of the sofa.

FIGURE 7 shows the brackets 108 attached to the frame of the sofa by screws 120 and attached to the beams of the supporting mechanism by bolts 94. The supporting mechanism is the same as that already described for the chairs of FIGURE 1 and corresponding parts are indicated by the same reference characters with a letter 'a' appended. Because of the greater length of the sofa, there are two plates 26a, and the invention can be applied to a long sofa with more than two plates 26a. The structure shown in FIGURE 7 has as many beams 32a as there are plates 26a, but has only one beam 34a. This latter beam is of composite construction and includes more sections and center hubs than in a chair in order to accommodate for the increased length of the area across which the supporting means is required to extend.

The preferred embodiments of the invention have been illustrated and described, but changes and modifications can be made and some features can be used in different combinations without departing from the invention as described in the claims.

What is claimed is:

1. In an overstuffed piece of furniture of the class having a frame, a seat, and a bottom with springs for supporting the seat, the combination with said frame and springs of supporting means including a plate of substantial area in contact with the bottom below the springs thereof, two stiff beams extending across the bottom of the furniture under the plate and supporting the plate, the beams being in angular relation to one another and crossing at a mid region of said bottom, brackets at both ends of both beams connecting the ends of the beams to the frame of the furniture, and connections between the beams and the brackets adjustable angularly in a horizontal plane, whereby the supporting means is suitable for use with pieces of furniture having frames of different shape.

2. The combination described in claim 1 characterized by the beams being of composite construction and each having a mid portion that is connected with the mid portion of the other beam.

3. The combination described in claim 2 characterized by the connection at the mid portions of the beams being a center hub with sockets, and parts of the beams

beyond the center hub being stiff elements that project into the sockets for providing a composite structure with stiffness in a vertical direction for supporting the plate.

4. The combination described in claim 3 characterized by the center hub having four sockets that are in approximately right-angular relation to one another about a vertical axis but with two of the sockets that are intended to face rearwardly on the furniture at an angle somewhat less than 90° to one another, and two of the sockets that are intended to face forwardly at an angle somewhat greater than 90° to one another.

5. The combination described in claim 3 characterized by the sockets having a height substantially equal to the height of the ends of the beams that fit into said sockets, but the sockets having horizontal widths somewhat greater than the width of the parts of the beams that fit into them whereby the beams are angularly adjustable with respect to one another in a horizontal plane to accommodate the supporting means to furniture of varying width from front to back.

6. The combination described in claim 3 characterized by the beams being of round tubular section throughout a substantial part of the length but having sections of reduced outside diameter and greater structural thickness at the ends which project into the sockets.

7. The combination described in claim 6 characterized by the sections of reduced diameter being solid rods that extend into the tubular sections at one end and into the sockets at the other end, and means for preventing axial movement of the rods with respect to the tubular sections.

8. The combination described in claim 3 characterized by the supporting means having some resiliency that permits limited vertical movement of the plate when a person sits on the seat, and screw means connected with the center hub and extending upwardly into contact with the plate, the screw means being vertically adjustable to move the plate up and down with respect to the beams.

9. The combination described in claim 3 characterized

by the hub sockets being tapered in a horizontal plane and the hub being divided into upper and lower parts along a horizontal plane through the sockets at their maximum widths, and fastening means holding the parts 5 of the hub in assembled relation to one another.

10. The combination described in claim 3 characterized by each of the brackets having two legs generally normal to one another and connected to the frame of the chair at opposite sides of frame elements that are joined at 10 a corner of the chair, each of the brackets having a slot opening therein, and fastening means for connecting the beams with the brackets including screw means extending through the slots and through flattened ends of the beams.

11. The combination described in claim 10 characterized by each bracket being a rigid element and serving as a brace for holding the elements at the corners of the frame together, and the slot in each bracket being curved throughout at least a part of its length about a center located approximately on the line of meeting of 15 the elements at the corner of the frame, the screw means being a bolt.
